DREDGE BUCKET AND LIP ASSEMBLY

William H. Stires, High Bridge, N. J., assignor to
 Taylor-Wharton Iron & Steel Company, High
 Bridge, N. J., a corporation of New Jersey

Application June 15, 1932, Serial No. 617,467

18 Claims. (Cl. 37—141)

In connection with dredge buckets and more particularly hooded buckets of the endless elevator type, there is a demand for so-called "inside-outside lips", that is to say, lips that straddle the hood and have flange portions overlapping and secured, respectively, with relation to the inner and outer walls of the bucket. But, heretofore and before my invention, buckets so equipped suffered the disadvantage that they were costly in upkeep because the lips required to be riveted to place and when worn much valuable time was lost in removing the old rivets and in riveting the replacements, aside from the fact that there was considerable shearing strain on the rivets which entailed frequent repairs. Moreover, the construction and arrangement, making for overlapped and offset areas or projections, often resulted in choking of the bucket.

Objects of my invention are to obviate the disadvantages of the old practice and to provide a lip that may be secured without the aid of rivets; is quickly and easily attachable and detachable; and is free from choking propensity.

The nature, characteristic features and scope of the invention more readily will be understood from the following description taken in connection with the accompanying drawing, forming a part hereof, wherein—

Figure 1 is a longitudinal sectional view of a dredge bucket and lip assembly embodying the improvements.

Fig. 2 is a section on line 2—2 of Fig. 1.

Fig. 3 is a section on line 3—3 of Fig. 2.

Fig. 4 is a section on line 4—4 of Fig. 1.

Fig. 5 is a section on line 5—5 of Fig. 1; and

Fig. 6 is a section on line 6—6 of Fig. 1.

The bucket 5, except as hereinafter specified, may be of standard or usual construction. And lip 6 may have any desired form of cutting edge 7.

According to my invention the hood, with relation to its accommodation of the lip, is formed on the inside with fore and aft lip seating areas defined by shoulders 8, which forwardly vanish in the body of the hood and which rearwardly terminate in recesses or pockets 9, which establish a sort of hinge-like connection for the terminals of the lip and prevent spreading thereof. Externally the hood is equipped with paired ribs 10 whereby means are provided, which, in conjunction with the hinge lock, rigidly secures the lip to place.

Lip 6 is curved to match the curvature of the hood and has an outside depending escutcheon or apron 11 and inside aprons 12. Aprons 12 have rabbeted portions 13 in coincidence with

rabbeted portions 14 of the hood so that the lip has shoulders 15 and 16 which, respectively, bear on the marginal wall of the hood and on the inside shoulder 8 thereof. The rounded terminals 17 of the lip enter the anchoring pockets 9 and thus hold down the rear of the lip and effectively operate to prevent spreading thereof. Figs. 4 and 5 aptly show how the hood and inside aprons have mutual rabbeted provisions to insure flush seating of the lip and thereby the avoidance of conditions making for choking.

I am mindful that with a lip and bucket assembly, such as hereinbefore described, riveting or other usual means well might be employed to secure the front of the lip. However, it is a merit of the invention that its simplicity is preserved even to the extent of the front lock. For that purpose the front of the lip is formed with depending lugs 18 to fit between the ribs 10; and the ribs and lugs have registered eyes to accommodate a taper pin or bolt 19. Reasonable clearance is allowed between the seating surfaces of the lip and bucket so that when the taper or wedge fastening is applied a rigid fit is established.

It will be manifest from the description and illustration that the improved assembly not only combines simplicity, sturdiness and efficiency but also makes for clean dumping buckets.

What is claimed as new—is:—

1. A chain dredge bucket having a lip seat, in combination with a separable lip, means on the bucket and cooperating means on the lip and relatively engageable so that the lip may be supported on its end extremities in upraised position and then eased through a circumscribed arc to seating position, and means for securing the lip in operative relation with the bucket.

2. A chain dredge bucket embodying a hood formed with sockets constituting hinge elements for a straddling lip, and a lip having terminals formed in coincidence with said sockets and engageable therewith to permit the lip to be rocked through a circumscribed arc to or from straddling relation with the hood, and means for securing the lip in effective seating relation.

3. A chain dredge bucket having a hood formed with a lip seat and with sockets below and extending rearwardly of the lip seat and constituting hinge elements for a lip, and a lip having terminals formed in coincidence with said sockets and engageable therewith whereby the lip may be rocked through a circumscribed arc to or from straddling relation with the hood, means for cen-

tering the lip, and means for securing it in quickly detachable relation.

4. A chain dredge bucket whereof the hood is kept up to maximum cubic capacity by a lip having inside and outside straddling portions, the hood having inside rabbeted areas to insure flush seating of the inside straddling portions and which merge into pockets, and a lip of the type recited having terminals adapted and arranged 5 to be cradled in such pockets whereby the lip may be readily swung to or from straddling position, and means for securing the lip.
5. A chain dredge bucket whereof the hood is kept up to maximum cubic capacity by a lip having inside and outside straddling portions, the hood having inside rabbeted areas to insure flush seating of the inside straddling portions and which merge into pockets, and a lip of the type recited having terminals adapted and arranged 10 to be cradled in such pockets whereby the lip may be readily swung to or from straddling position, the outside straddling portion and the hood having cooperative guides for centering the lip.
6. A chain dredge bucket whereof the hood is kept up to maximum cubic capacity by a lip having inside and outside straddling portions, the hood having inside rabbeted areas to insure flush seating of the inside straddling portions and which merge into pockets, and a lip of the type recited having terminals adapted and arranged 15 to be cradled in such pockets whereby the lip may be readily swung to or from straddling position, the outside straddling portion and the hood having cooperative guides for centering the lip, and 20 means whereby said guides may be availed of to secure the lip in quickly detachable relation.
7. A chain dredge bucket having a hood formed with a lip seat and with cored pockets below and beyond the lip seat and having outwardly flaring 25 top walls and constituting one element of a hinge connection for a straddling lip.
8. A chain dredge bucket formed inside with downwardly curved rabbeted areas terminating rearwardly in cored pockets adapted to receive a 30 lip of the swinging type.
9. A chain dredge bucket having a lip seat with rabbeted areas inwardly thereof to provide for substantial flush seating of a straddling lip and having undercut outwardly flaring pockets to receive 35 swingingly the ends of the lip, and lip centering and locking devices formed externally of the bucket.
10. A lip formed with a hood seat defined by spaced apron extensions, said lip having rounded 40 terminals constituting pivots.
11. A lip formed with a hood seat defined by spaced apron extensions, said lip having centering and locking devices of the quickly releasable 45 type, the terminals of the lip having blunt noses constituting pivots.
12. A dredge bucket having a lip seat and provided externally with abutments and internally with pockets having rounded bottoms, and a lip 50 having end extensions fulcrumed in said pockets and having apron extensions within and without

the bucket and having a part engageable with the abutments.

13. A dredge bucket having a rim seat adapted and arranged for the reception of a straddling lip and having below the rim seat undercut pockets constituting hinge elements for the lip, and a lip adapted to the seat and having outside apron extensions and having inside apron extensions substantially flush seated with the inside wall of the bucket, said lip having blunt nose terminals to establish hinge connection with said pockets, and means externally of the pocket and lip for securing them in quickly detachable relation.

14. A dredge bucket having a rim seat adapted and arranged for the reception of a straddling lip and having below the rim seat undercut pockets constituting hinge elements for the lip, and a lip adapted to the seat and having outside apron extensions and having inside apron extensions substantially flush seated with the inside wall of the bucket, said lip having blunt nose terminals to establish hinge connection with said pockets, and means on the front of the bucket to tighten the lip in normal posturing relation.

15. A chain dredge bucket in combination with a straddling lip having aprons which respectively lap the inside and outside walls of the bucket, the inside wall of the bucket and the ends of the lip having mated bearings providing for tilttable mounting of the lip so that it may be applied 25 or removed by rocking it through a circumscribed arc, and interlocking provisions for the bucket and lip, including means for tightening the lip.

16. A chain dredge bucket having its rim and inside wall portions formed to accommodate a 30 replaceable lip, a lip contoured to fit the edge of the bucket and having inside and outside bucket lapping portions, means on the bucket and cooperating means on the lip and relatively engageable so that the lip may be initially supported in upraised position and then eased 35 through a circumscribed arc to proper seating relation with the bucket whereupon said means on the bucket and the cooperating means function as an end lock for the lip, and means for taking 40 up relative looseness.

17. A chain dredge bucket having lip seating areas for cooperation with a replaceable lip, posturable in a direction towards the bottom of the bucket, in combination with such lip, pivot 45 members on the bucket and cooperating pivot members on the lip relatively engageable so that the lip may be sustained on end in uplifted position and then swung downwardly to its seat whereupon said pivot members function as end locks for the lip, and cooperating means on the lip and bucket for compensating for relative looseness of fit.

18. A dredge bucket comprising a hood having a rim seat and bearing surfaces below the same for the swinging mounting of a lip, and a lip having terminals engageable with said bearing surfaces to permit it to be moved through a circumscribed arc into straddling relation with the rim.

WILLIAM H. STIRES.
